UNITED STATES PATENT OFFICE.

MARY C. SHINN, OF SEATTLE, WASHINGTON.

ROTARY SURFACE-BRUSH.

1,374,476.

Specification of Letters Patent. Patented Apr. 12, 1921.

Application filed August 7, 1919. Serial No. 315,990.

To all whom it may concern:

Be it known that I, MARY C. SHINN, a citizen of the United States, residing at Seattle, in the county of King and State of Washington, have invented certain new and useful Improvements in Rotary Surface-Brushes; and I do hereby declare the following to be a full, clear, and exact description of the invention, such as will enable others skilled in the art to which it appertains to make and use the same.

This invention relates to scrubbing or polishing apparatus and more particularly to a power driven and manually applied brush.

The present improvement relates to that type of brushes which are designed to rotate over and scrub and clean or polish a given surface and in which the brush is directed by a motor and mechanism connecting the same to the brush, the whole being compactly organized for convenient handling. Another object of the present invention is to provide for the efficient driving of a pair of brushes mounted for rotation about parallel axes, the bristles of the brush projecting from a disk and terminating in a plane parallel to the outer or lower surface of the disk. A further object of the present invention is to provide a power driven brush organized into a self contained unit and with which the brush is relatively yieldingly mounted.

A further object of the invention is to provide a power driven rotary brush structure in which the casing is provided to enclose the motor and on which casing the brushes are so disposed as to be readily applied with their active bristle ends in engagement on a surface to be polished, the brushes and motor organized and being so arranged that the unit of the motor and a part of the housing may be availed of to secure the desired pressure of the brushes to the surface being operated upon. In addition to the above objects a further object is to provide a handle structure extending in such position from the housing as to be used as a lever when the outer end of the handle is fulcrumed on a suitable support as for instance, on the surface being treated and further to provide for a ready shifting of the device in any desired direction with minimum resistance over the surface.

With the above and other objects in view as will be rendered manifest to those versed in the art, the invention consists of the

construction, the combination, and in details and arrangements of the parts as more particularly described hereinafter relative to the embodiment of the invention illustrated in the accompanying drawings, in which:

Figure 1 is a side elevation of the brush as applied to a surface.

Fig. 2 is a bottom or underneath plan view of the device.

Fig. 3 is an elevational view of the device showing one-half or section of the casing removed to disclose the motor and driving shaft connection, the brush mounting being in section.

Fig. 4 is a detail view of the gear organization taken on line 4-4 of Fig. 3.

Fig. 5 is a cross section at 5-5 of Fig. 3.

In the illustrated embodiment of the invention a motor casing 2 is formed of suitable sections or parts which may be appropriately secured together as by screws 3, the casing inclosing a suitable form of electric motor 4 having its shaft apparatus journaled in an upright position with respect to the plan of use of the apparatus. The motor shaft comprises an upper section 5 which is longitudinally splined or grooved as at 6, to match with a complementary section 7, whereby the latter section can be shifted axially but is normally shifted outwardly to a limited position by means of a spring 8, in this case shown as mounted in a housing 9 to the splined sections of the shaft, therefore, the shaft is extensible in length but rotates as a unity.

The housing 2 has at its lower side a hub 10 having at its lower end an inwardly projecting flange integral therewith to form a stop against the outer movement of the lower shaft section 7 and the depending section 11 extends through the hub and is revolvably journaled in a yielding carrier 12, which fits on the hub 10 for sliding movement on the non-rotative hub. This slide or carrier has formed in its lower portion a shallow chamber 13, in which lies a train of gears, the pinion or master gear 14, of which is secured on the lower end of the shaft stem 11. Directly engaging the master gear is another gear 15, having a shaft 16 on which is mounted a flat disk-like brush 17, this operating below the bottom of the slide or carrier 12 and having its bristles arranged in a plane brush rotating bodily about the axis of its shaft 16. A

similar brush is provided on the opposite side of the gear 14 and has on its shaft a gear 18 which engages an intermediate gear 19, which meshes with the driving gear 14, the object of this system of gearing being to secure the rotation of the brushes 17, in a reverse direction or so that their action sets up counterbalanced resistance when the motor is started and the brushes are operating over a surface to be polished as in Fig. 1.

One of the important features of the present invention is the provision of means for readily controlling the pressure when the brushes 16 are forced onto the surface being treated and therefore, which means provides for a ready shifting of the brush in the desired direction. To secure these objects the casing 2 is shown as having extended through one side a tube or neck 20 forming 20 a handle, which has a downwardly turned end portion 21, preferably provided with a roller 22, which decreases the resistance of shifting the device over the surface to which it may be applied and on which it is operating. This handle 20 is supported in raised position from the floor by means of the roller 22, so that the handle can be readily grasped by the hand, the roller forming a fulcrum to guide the brushes as may be desired. Also the handle provides a convenient guard for the electrical current wires 23, which may be led into the handle through an opening 24, provided for that purpose. Any suitable construction may be utilized 35 such as the switch designated at 25, and as here shown is preferably located adjacent the junction between the housing and the handle or lever 30, and is thus readily engaged by the thumb or fore finger of the operator to control the operation of the motor.

By yieldingly mounting the motor housing with respect to the slide or carrier 12, it will be seen that the bristles of the brushes 45 will be protected against being deflected or bent unduly by the initial movement of the housing under the pressure of the hand when applied to the handle so that the operator can by the sense of touch readily determine 50 the amount of pressure that is being applied to the brushes.

In addition to the above advantage by the provision of the yielding means between the brushes and the motor and its bearings this 55 yielding means tends to overcome excess vibration of the parts and also prevents the device from bodily and vertically jumping or moving as it is shifted over irregularities in the surface being treated.

While I have described the brushes in my 60 apparatus to be provided with bristles, as the commonly used means for scrubbing, yet I have designed the apparatus more partic-

ularly for cleaning and polishing hard or metal surfaces, and for removing paint, etc., 65 from old surfaces and preparing the same for fresh paint or finishing coats, and for such purposes I use small but stiff wires instead of bristles for the brushes. These wires I place very thickly together so that 70 the bearing surface of the points of the wires nearly covers the surface to be polished, yet in the rotary motion the points naturally divide sufficiently to make each of the points individually act against the surface, and being stiff they very quickly remove any substance from such surface and leave it clean.

What I desire to claim is:

1. A rotary brush device comprising a 80 shaft, a housing providing bearings for said shaft, one of said bearings extending beyond the outer wall of the housing to form a hub, a brush carrier provided with brushes slidably mounted upon said hub, said shaft being longitudinally extensible, gear connections between said shaft and said brushes and a motor on the shaft within the housing for imparting a rotative movement to the shaft.

2. In a rotary brush device, a motor and a housing therefor, a brush carrier, said brush carrier provided with sockets on opposite sides, a hub on said motor housing slidably fitting into one of said sockets, a chain of 85 gears fitting into the other of said sockets with the outer side of said gears substantially coplanar with the face of said carrier, shafts carrying said gears pivotally mounted in said carrier, and brushes mounted on 90 a pair of said gears, and means interconnecting said motor and said gears to rotate said brushes.

3. In a rotary brush device, a motor provided with a housing, an extension formed 105 on the housing and projecting therefrom to form a handle, a supporting roller at the outer end of the extension, a brush carrier provided with rotary brushes and means interconnecting said motor and brushes to rotate 110 the brushes.

4. A brush device comprising a motor provided with a shell, and with a shaft said shell extending into a hub around the motor shaft and also having an extension at an 115 acute angle to said hub forming a hollow handle, a roller mounted on the end of said handle, circuit wires mounted in said hollow handle, a brush carrier, said brush carrier being slidably upon said hub, brushes rotatably mounted in said carrier, and means interconnecting said brushes and said motor to provide for the rotation of said brushes by said motor.

In testimony whereof I affix my signature. 125
MARY C. SHINN.
